UNITED STATES PATENT OFFICE.

FRANK S. SPARKS, OF SPRINGFIELD, OHIO, ASSIGNOR OF ONE-THIRD TO FRANK L. WALKER, OF DAYTON, OHIO.

CLOTHES-PRESSING MACHINE.

1,244,653.

Specification of Letters Patent. Patented Oct. 30, 1917.

Application filed April 28, 1913. Serial No. 784,123.

To all whom it may concern:

Be it known that I, FRANK S. SPARKS, citizen of the United States, residing at Springfield, in the county of Clark and 5 State of Ohio, have invented certain new and useful Improvements in Clothes-Pressing Machines, of which the following is a specification.

My invention relates to ironing machines 10 and particularly to clothes pressing machines, of that type in which a volume of live steam is discharged upon and through the articles operated upon, which are simultaneously subjected to pressure.

15 The object of the invention is to simplify the structure as well as the means and mode of operation of such machines, whereby they will not only be cheapened in construction, but will be more efficient in use, 20 easy of operation, and unlikely to get out of repair.

Such machines as usually constructed embody a presser head adapted to be drawn down upon the article operated upon, after 25 which a valve is operated to discharge the live steam upon and through said article.

There is commonly employed with each machine a suitable boiler usually of the flash or quick generating type. The 30 machines are necessarily very extravagant in their use of steam, requiring frequent replenishing of the water supply within the boiler. The water is usually supplied to the boiler by a hand operated pump. It is 35 necessary for the operator to leave his position in front of the machine at frequent intervals, in order to replenish the boiler.

Should he neglect to do this there is grave 40 danger of the supply of water within the boiler becoming exhausted, permitting the boiler head and flues to become overheated, thereby burning or otherwise damaging such parts and upon the subsequent introduction of water, causing an explosion of 45 the boiler.

A further object of the invention is to provide means for insuring the safety of the boiler and speed of operation of the machine, by supplying to the boiler at each operation a quantity of water substantially equivalent to the volume of steam discharged, such supply of water being automatically controlled by the operation of the machine, obviating any necessity of the operator interrupting his work in order to

give his attention to the boiler. Furthermore the admission of water in small quantities at frequent intervals does not materially lower the temperature or arrest the production of steam as does a large quantity of water, and obviates extremes of expansion and contraction, thereby prolonging the life of the boiler.

With the above primary and other incidental objects in view as will more fully appear in the specification, the invention consists of the features of construction, the parts and combinations thereof and the mode of operation of their equivalents, as hereinafter described and set forth in the 70 claims.

Referring to the drawings Figure 1 is a side elevation of the assembled machine to which the invention, forming the subject matter hereof, has been applied. Fig. 2 is 75 a rear elevation of the assembled machine. Fig. 3 is a vertical sectional view of the water supply pump. Fig. 4 is a detail sectional view of the oscillatory connection of the gas supply conduit.

Like parts are indicated by similar characters of reference throughout the several views.

Referring to the drawings, 1 is a main frame or pedestal upon which is supported 85 a deck or table 2. Projecting upward from the table 2 is a pressing pad or buck 3, upon which is placed the work to be operated upon. Pivotaly supported upon arms 4 projecting above the table or deck 2, is an oscillatory head comprising two curved arms 5, carrying a presser head 6, adapted upon oscillation of the arms 5 to register with and bear upon the buck 3. As usually constructed the head 6 is hollow, forming a live steam 90 chamber, to which steam is conducted from a boiler 7.

The live steam leaves the boiler 7 through the conduit 8, thence through a separator or purifier 9 from which it passes through the 100 conduit 10, to a chamber 11, mounted concentric with the pivotal connection of the arms 5. A conduit 12 is pivotally connected with the chamber 11 through a suitable stuffing box or gland, whereby the conduit 105 12 may be oscillated about its connection with the chamber 11 in unison with the oscillation of the arms 5. The conduit 12 leads to the head 6, but before being introduced into the steam chamber within said head 6, 110

the steam is conducted adjacent to a gas burner 13 by which it is super heated, passing thence through the conduit 14 to the interior of the head 6.

5 In the conduit 14 there is located a steam control valve 15. Steam is admitted to the chamber within the head 6 by the operation of the valve 15 and passes thence through the porous face of the steam chamber to the 10 article operated upon, which is positioned upon the buck.

The curved arms 5 are joined one to the other and extended rearward in the single arm 16. A retracting spring 17 is attached 15 at one end to the main frame or pedestal 1 and at its opposite end to the rearward extending arm 16. This retracting spring 17 is adapted to normally elevate the presser head 6, by oscillating said head upward 20 about its pivotal connections with the arms 4.

The head 6 is pulled downward against the tension of the spring 17 by means of a handle or grip 18, until a detent or latch 19 carried by the rearward arm 16, engages a 25 shoulder 20 in a vertical reciprocatory bar 21. The bar 21 is connected at its lower end with a foot lever 22. After the head has been drawn downward by means of the handle or grip 18, until the porous face of 30 the head is in contact with the goods to be operated upon at which time the latch or detent 19 has engaged the shoulder 20 of the bar 21, pressure is applied to the foot lever 22 tending to cause an upward movement of 35 the bar 21, which will effect a further depression of the head 6, causing it to bear with great pressure upon the work.

While the work is under pressure the valve 15 is operated to discharge live steam 40 through the chamber of the head 6, and thence upon the work. The detent 19 is then disengaged from the shoulder 20 of the bar 21 by means of a trip rod 23, carrying at its forward end a finger pull 24.

45 As thus far described the construction is of a common form now in general use, and forms no part of the present invention. Such a machine is shown in detail in patent to A. J. Hoffman, No. 928,199, July 13, 1909. 50 As now constructed it is necessary for the operator to leave his position in the front of the machine at frequent intervals to replenish the supply of water within the boiler 7.

55 To maintain the supply of water within the boiler 7 at a constant level, regardless of the rapidity with which the machine may be ordinarily operated, there is provided in the lower portion of the main frame 1 a 60 supply pump comprising a cylinder 25 within which reciprocates a piston 26. The cylinder 25 is securely supported in a suitable bracket 27, while the piston 26 is provided with a suitable bearing in the upper portion 65 of the main frame 1.

At its upper end the piston 26 is pivotally connected with a flat bar 28, having a C shaped notch or recess 29 therein. A stud 30 carried upon the rearward extending arm 16 of the head, engages within the C shaped recess 29 of the bar 28 as shown in Fig. 1. 70

It is obvious that a suitable slot may be employed in lieu of the C shaped recess. However the lateral opening in the recess is provided, in order that the bar 28 may be 75 engaged with or disengaged from the stud 30 at will. A flat spring 31 carried by the plunger 26 and bearing upon the side of the bar 28 tends to prevent the accidental disengagement of the bar and the stud. 80

The pump cylinder 25 is connected through a conduit 32 with a suitable reservoir 33 or other water supply. A conduit 34 leads from the pump cylinder 25 to the boiler. The pump may be of any suitable 85 or desirable construction. However in the drawings the pump cylinder has been shown with a tapered or conical seat 35 immediately above and concentric with the inlet orifice 36 from the supply conduit 32. Normally resting on this inclined or tapered seat 35 is a ball valve 37 adapted to close the orifice 36. Two or more pointed studs 38 extend within the cylinder 35 above the ball valve 37 and limit its upward movement, but permit sufficient movement to open the inlet orifice 36 to admit a supply 90 of water. 95

At its upper extremity the cylinder 25 is provided with an internal rabbet or annular recess 39, in which is located a band of packing material 40. Resting upon the packing material 40, within the recess 39, surrounding the piston 26, is a sleeve 41, free to move longitudinally under the influence of a compression cap 42, screw threaded upon the exterior of the cylinder 25. 100

At each oscillation of the head 6 downward upon the work the pump piston 26 is 110 elevated to draw a charge of water into the cylinder 25 through the inlet orifice 36. Upon the return movement or elevation of the head 6, the pump piston 26 is depressed to discharge the water from the cylinder 115 25, through the conduit 34 to the boiler 7. A check valve 43 is provided in the conduit 34 to prevent the return flow of the water from the boiler.

By the slotted connection 29 the initial 120 movement of the head 6 in either direction is independent of the pump piston 26. That is upon the oscillation of the head 6 in either direction, the stud 30 upon the arm 16 will travel throughout the length of the 125 slot or recess 29 before it begins to reciprocate the piston 26. This independent initial movement of the head gives to the head momentum sufficient to overcome the 130 inertia of the pump piston, thereby requir-

ing less power to operate the head 6 in either direction of travel.

The capacity of the water supply pump is so proportioned that the charge of water supplied to the boiler 7 at each oscillation of the head 6 will approximately compensate for the quantity of steam discharged upon each operation of the head. It has been found in actual practice that after a full day of continual operation the water level within the boiler has been varied but very slightly. Inasmuch as the water supply to the boiler requires no attention by the operator it has been found that the results accomplished by the operator has been very materially increased. Furthermore the use of this device entirely obviates any danger of the boiler being burned or becoming overheated, whereby an explosion may occur by the introduction of cold water. The operator is enabled to give his full and continuous attention to the work in hand and to dismiss the care of the boiler from his mind.

To obviate the possible leakage of gas there is provided upon one of the supporting arms 4 concentric with the pivotal connection of the head, a chamber or housing 52, to which leads a gas supply conduit 53. This housing 52 is provided with a longitudinal bore 54, in axial alinement with the pivotal connection of the head, terminating in a tapered seat 56 and intersected by a lateral bore 55 with which the supply conduit 53 communicates. The chamber or housing thus formed becomes substantially an elbow connection between the supply conduit 53 and the gas conduit 61 hereafter mentioned. Projecting within the longitudinal bore 54, is a hollow trunnion 57, having a tapered or conical head 58 conforming to the tapered seat 56 upon which it rests. A body of packing material 59 is provided about the hollow trunnion 57, adjacent to the head 58, upon which bears the usual packing gland 60. The tapered head 58 and the corresponding seat 56 are ground to a close fit one with the other. The construction is such that the hollow trunnion 57 may be oscillated within the housing 52, without the leakage of gas between the head 58 and the seat 56. Leading from the hollow trunnion 57 is a gas conduit 61, extending to the gas burner before mentioned upon the head 6. This gas conduit 61 is constructed of pipe or metallic tubing throughout and oscillates in unison with the head 6. This construction provides a conduit which always will be safe against leakage of the gas.

From the above description it will be apparent that there is thus provided a device of the character described, possessing the particular features of advantage before enumerated as desirable, but which ob-

viously is susceptible of modification in its form, proportion, detail construction or arrangement of parts without departing from the principle involved or sacrificing any of its advantages.

While in order to comply with the statutes, the invention has been described in language more or less specific as to certain structural features it is to be understood that the invention is not limited to any specific details, but that the means and construction herein described comprise but one mode of putting the invention into effect, and the invention is therefore claimed broadly and in any of its possible forms or modifications within the scope of the appended claims.

Having thus described my invention, I claim,

1. The combination of a clothes pressing machine, a boiler from which steam is supplied to the pressing machine, a pump supplying water to the boiler, and an actuating connection between the pump and pressing machine by which the pump is operated by the operation of said machine.

2. The combination of a clothes pressing machine, a boiler from which steam is supplied to the clothes pressing machine, a water supply device for supplying water to the boiler, an actuating connection between the pressing machine and the water supply device for automatically regulating the supply of water by the operation of the pressing machine.

3. The combination of a clothes pressing machine, a boiler supplying steam to the pressing machine, a water supply device supplying water to the boiler, and an actuating connection between the water supply device and the pressing machine by which the said device will be automatically operated to supply water to the boiler at each operation of the pressing machine.

4. The combination with a clothes pressing machine including a movable presser head, a boiler supplying steam to the pressing machine, a water supply device supplying water to the boiler, and means whereby at each operation of the movable presser head of the pressing machine the water supply device is operated to supply water to the boiler.

5. The combination of a clothes pressing machine having a movable head, a boiler supplying steam to the pressing machine, a water supply device supplying water to the boiler, and an actuating connection between the water supply device and the pressing machine head.

6. The combination of a clothes pressing machine, including a movable member, a boiler supplying steam to the pressing machine, a water supply device supplying water to the boiler, a sliding actuating connection

between the water supply device and movable member of the pressing machine whereby the water supply device will be operated throughout one portion of the movement of 5 said movable member, said member moving independent of the water supply device throughout the other portion of its movement.

7. The combination of a clothes pressing 10 machine, including a movable member, a boiler supplying steam to the pressing machine, a water supply device supplying water to the boiler, an operating connection for the water supply device having an elongated opening therein, and a stud carried by 15 the movable member and engaging in the recess within which it moves idly throughout the extent of the recess during the initial movement of the said movable member and 20 thereafter moves said connection in unison therewith to actuate the water supply device.

8. The combination with a clothes pressing machine, including a movable member, 25 a boiler supplying steam to the pressing machine, a water supply device supplying water to the boiler, and an actuating connection between the water supply device and the movable member of the pressing machine where- 30 by the water supply device will be automatically operated to supply a predetermined quantity of water to the boiler at each opera- 35 tion of the pressing machine.

9. Means for regulating the supply of 35 feed water to the generator supplying steam to a clothes pressing machine comprising a feed water control member, a water supply conduit leading therefrom to the generator, and an actuating connection between the 40 feed water control member and the clothes pressing machine whereby the operation of said machine will operate the feed water con-

trol member to supply water to the generator.

10. The combination with a clothes press- 45 ing machine, and a steam generator therefor, of means for regulating the supply of feed water to the generator which supplies steam to said pressing machine comprising a feed water control member, a water supply con- 50duit leading therefrom to the generator, and an intermittently operated actuating connection between the clothes pressing machine and the feed water control member whereby the feed water control member will be op- 55 erated by the operation of the clothes press- 60 ing machine throughout a portion of the movement of said pressing machine, a portion of the movement of said pressing machine being accomplished independent of the operation of the water control member.

11. The combination with a garment pressing machine having a movable presser head, and a steam generator therefor, of means for automatically controlling the sup- 65 ply of feed water to the said steam generator, comprising a feed water control member, a water supply conduit leading from the feed water control member to the steam generator, and operating element common to both the 70 presser head and the feed water control mem- 75 ber and operative connections between the operating element and the presser head, and between the operating element and the feed water control member, whereby both the presser head and the feed water control member will be actuated by the common operating element.

In testimony whereof, I have hereunto set my hand this 22nd day of April, 1913.

FRANK S. SPARKS.
